UNITED STATES PATENT OFFICE.

ERNEST BISSON, OF PARIS, FRANCE.

MARINER'S COMPASS.

SPECIFICATION forming part of Letters Patent No. 289,209, dated November 27, 1883.

Application filed July 17, 1883. (No model.)

To all whom it may concern:

Be it known that I, ERNEST BISSON, of Paris, France, have invented certain new and useful Improvements in Mariners' Compasses, intended more particularly for use on iron vessels; and I do hereby declare that the following is a full and exact description thereof.

My invention may be used with or without any other suitable precautions for preventing the disturbance due to the magnetic action of the vessel, or of anchors and chains, iron masts, &c. It is peculiarly effective in allowing an easy and prompt correction of disturbances of a temporary character, such as the raising and lowering of the smoke-pipe in steamers having telescopic chimneys.

One important part of the invention is an alidade carrying one or more magnetic bars, with provisions for changing the alidade and its connections into various positions relatively to the needle, which is inclosed within the circuit thus traversed. I employ two needles, one above and one below the trunnions.

In carrying the invention into practice, I provide a copper box containing two compass-cards, each with an independent magnetic needle and mounted one over the other. The box has a glass top, and is made in two parts joined together by screws. The glass top is perforated in the center and provided with a barrel or bush, permitting a shaft to extend through the top and allow its being turned, as required, by a button on the outer end. The shaft carries an internal alidade, on which are mounted two bar-magnets. The fixed bush in the center of the top is also fitted to form a bearing for an external alidade. (Not shown.) The whole is suspended in an ordinary gimbal-ring by means of trunnions, as usual. The two magnetic needles are carried on screw-pivots tapped through cross-bars in a central supporting-frame of copper.

The following is a description of what I consider the best means of carrying out the invention.

The accompanying drawing forms a part of this specification and is a central vertical section.

A is a copper box; B, the cover; C, the plate-glass in the cover; C', a fixed bushing or hub of metal in the center of the cover; E, a frame in the interior of the box to support the

needles; E', a cross-bar thereof. G is the internal alidade. It carries two bars, N S, N' S', of magnetized steel. This may be turned, as required, in various directions by turning the shaft G, which extends up through the hub C' and is turnable by a button, H, which latter can be removed when it is required to take off the cover B of the box.

J is the pivot for the upper needle, and J' the pivot for the lower needle. The upper pivot, J, is tapped through the cross-bar F. The lower pivot, J', is tapped through the bottom of the box.

M M' is the upper magnetic needle, delicately mounted on the pivot J in the ordinary manner. It carries a compass-card, K.

M' M' is the lower magnetic needle. It is of the same length as the upper needle, M, but considerably heavier. It is mounted on the lower pivot, J', and carries a compass-card, K'. The height of either or both these needles may be regulated by turning the corresponding screw-pivots, J and J'.

R is a horse-hair stretched up and down in the position represented. It might, without explanation, be understood from the drawing that the uprights of the frame E are in the same plane as the hair R. This is not the fact. It is so shown in the drawing only for convenience. The plane of the uprights E may be transverse to the plane of the drawing.

P is a column or post, sustaining, by means of a hinge, Q, two mirrors, O, flexibly connected together by a hinge, O'.

S' is an adjusting-screw. By means of the hinges and this adjusting-screw the mirrors O O' may be easily set so as to show to the observer both the compass-cards K and K', the upper card, K, being reflected in the upper mirror, and the lower card, K', being reflected in the lower. These mirrors stand at a different angle and show the images close together. The trunnions by which the box is supported on the gimbal-ring D are low, but I cause the box and its contents to maintain their equilibrium by loading the base of the box with lead or other heavy weights. The magnetic needles M M', being of different weights and arranged with their axes or pivots in the same vertical line, are influenced to different extents by the earth-currents and by the magnet-bars on the alidade or alidades. In adjusting my

compass on a new shaft or in a new position on the old one, the direction of both the needles is carefully noted, and if found to indicate wrongly the alidade G is turned by means 5 of the button H and pin G' until the influence of the magnets N S and N' S' counteracts the disturbing influence of the iron of the vessel, or of anchors, cables, guns, or the like in the vicinity, and causes them to indicate correctly. 10 In case both cannot be correctly adjusted, the alidade is turned until one needle indicates correctly, and that needle is depended upon for correct indications in all subsequent uses of the instrument. The two needles, mounted 15 one above the other, and of unequal weights, tend to correct each other. The alidade corrects both. For the best operation of my invention the two needles should be placed about ten or fifteen centimeters apart. I attach im- 20 portance to the fact that the needles are of equal length and of unequal weight; also, to the fact that the mirrors are hinged together and capable of adjustment to allow both compass-cards to be seen simultaneously; also, to the fact that the gimbal-ring is low and about 25 equally distant from each of the two compass-cards; also, to the fact that all the delicate parts are inclosed within a tight box. Modifications may be made in the forms and proportions.

It is not essential that the distance of the magnetic bars N S, N' S' from the two needles shall be exactly equal. I prefer the arrangement shown. 30

I claim as my invention—

1. In a compass for iron vessels, the alidade 35 G, carrying short magnetic bars N S, N' S', in combination with the shaft G', extending upward through the hub C', and with the turning means, H, mounted above the latter, all arranged relatively to each other and to a compass-needle, M, as herein specified. 40

2. In a compass for iron vessels, the two mirrors O O, in combination with the two needles M M' and the two cards K K', as herein specified. 45

3. In a compass for iron vessels, the gimbal-ring D, suspended box A B, having a loaded base, one or more alidades, G, with means for adjusting the same, and two magnetic needles, M M', combined and arranged to serve as 50 herein specified.

In testimony whereof I have signed this specification in the presence of two subscribing witnesses.

ERNEST BISSON.
